FLOW BEAN

Richard A. Werts, Long Beach, Calif.

Application May 15, 1945, Serial No. 593,853

11 Claims. (Cl. 251—86)

1

This invention relates to means for cutting down, or beaning back, or substantially regulating the flow of fluids from oil wells and deals more particularly with flow control devices known as flow beans. An object of my invention is to provide a flow bean which is simple, sturdy, efficient and which is selective to vary the desired conditions of flow.

My invention deals with flow beans such as are commonly connected to either side of the cross of the "Christmas tree" of a well producing under high pressure conditions as distinguished from bottom hole flow beans. Especially in oil wells, the fluid passing upwardly in the well tubing or casing into the "Christmas tree" and out through the flow beans to storage, frequently carries a high proportion of sand and other abrasive particles. Conventional flow beans are designed on the needle valve principle in which a needle is adjustably positioned in a Venturi tube to vary the flow through the bean. The abrasive wearing action of the sand in the fluid and of the fluid itself which is under high pressure, deleteriously affects both the needle and the tube of conventional flow beans resulting in frequent repairs and replacement of the affected parts and a consequent expense and reduction in the production of the well. Another conventional flow bean is the positive choke type which, in addition to being non-adjustable, also loses efficiency because of wear due to abrasion.

Another object of my invention is to combine the best features of adjustable flow beans and positive choke flow beans and to provide a flow bean with a positive, yet selective, restriction to the flow of fluids therethrough, according to production or proration requirements under varying conditions of well pressure.

Another object of my invention is to provide a flow bean of novel construction and designed to resist abrasive wear to a high degree.

Another object of my invention is to provide a flow bean in which the fluid passing therethrough enters the body of the bean at a relatively slow velocity, thence through a thin orifice in which the velocity increases for an extremely short period of time and immediately decreases as it leaves the orifice, thereby reducing the length of time of the high velocity, resulting in a minimum of abrasive wear upon the surfaces of said orifice.

A further object of my invention is to provide a flow bean of the positive restriction type embodying means for selectively positioning one of

2

various sizes of restricting orifices in the line of flow of the flow bean.

A still further object of my invention is to provide a flow bean having means for completely shutting off the flow therethrough and which can be fully opened to flow for various purposes and for the particular purpose of blowing out and ridding the flow bean body of sand and other accumulations.

10 The various objects and features of my invention will be fully understood from the following detailed description of a typical preferred form and application of the invention, throughout which description reference is made to the accompanying drawings, in which:

Fig. 1 is a longitudinal sectional view of a flow bean embodying a preferred form of my invention;

Fig. 2 is a front view thereof, partly broken; 20 Fig. 3 is a cross sectional view of selective means for regulating the flow of fluid through the flow bean, the view being taken on the line 3—3 of Fig. 1.

In the embodiment of the invention which I have illustrated, the flow line from the well and particularly the cross of a "Christmas tree," is shown as a tube or pipe 10. The pipe 10 is connected to the flow bean housing 11, in the chamber 12 of which I have shown selector means 13 for controlling or regulating the flow of fluid from the pipe 10 through the chamber 12 and out through a pipe 14 connected to the housing 11 at a right angle to the pipe 10. I have shown the flow bean as further comprising a valve and seat 15 associated with the selector means 13 and located to control flow from the chamber 12 through the outlet pipe 14, manual means 16 for operating the selector means 13, and visual means 17 for indicating the selected position of said selector means 13.

40 The housing 11 which I provide, may comprise a tubular body 20 in which the chamber 12 is formed as a substantially cylindrical open-ended recess having an end wall 19 and a plate 21 serving as a closure for the chamber 12. I secure the body 20 and plate 21 together by means of studs 22 on a circular flange 23 of the body and nuts 24 in the ends of said studs which project through aligned holes 25 in the plate 21. I show the body 20 as a suitable casting having a radial boss 26 internally threaded at 27 for connection with the pipe 10, and an axial boss 28 internally threaded at 29 for connection with the pipe 10, and an axial boss 28 internally threaded at 29 for connection with the pipe 14.

I prefer to weld the end of the bosses 26 and 28 as at 30 to the respective pipes 10 and 14 to obtain a leak-proof fluid pressure receptive assembly having an inlet passage 31, an outlet flow passage 32 at right angles thereto, and a connecting chamber 12, said passage 31 comprising the longitudinal bore of the pipe 10 and the passage 32 comprising the longitudinal bore of the pipe 14 and an aligned opening 32^a in the body wall 19. I show the plate 21 as also comprising a casting and I provide said plate with a central outer boss 33 which extends in a direction opposite to the pipe 14. I provide the plate 21 with a central hole 34 for passage therethrough of a longitudinally disposed shaft 35 connecting the selector means 13 within the chamber 12 and the manual means 16 outside the housing 11. Leakage between the plate 21 and the shaft 35 is prevented by a stuffing box 36 which I show as packing 37 around the shaft 35 and a gland 38 threadedly engaged with an internal packing seat 39 in the boss 33. I prefer to provide a sealing gasket 40 between the outer face of the flange 23 of the body 20 and the related face of the plate 21 whereby both said gasket 40 and the shaft packing 37 effectively seal the chamber 12 against leakage. The arrangement of the parts which I have described, provides for a relative longitudinal offset between the center of the pipe 14 and the axis of the shaft 35. Accordingly, the body casting 20 has the boss 28 arranged substantially centrally thereof, and the flange 23 eccentrically in a direction away from the body boss 26.

The selector means 13 and the valve and seat means 15 are associated both physically and functionally. I provide a valve seat ring 41 in the body opening 32^a and show said seat as threadedly connected at 42. Said seat 41 comprises a flanged ring having an axial passage 43 aligned with the passages 32 and 32^a and having direct communication through an angled valve seat 44 with the chamber 12. I show a valve disc 45 having a beveled circular face 46 engaged with the seat 44 and having disc centering fins 47 guided in the passage 43 of the valve seat ring 41. I further provide the disc 45 with a central axial hole 47^a which, while relatively large, is smaller in area than the area of the inlet passage 31. I connect the disc 45 to a reduced end 48 of the shaft 35 which passes through an eccentric hole 49 in said disc and secure said disc on the shaft by a nut 50.

The selector means 13 which I provide comprises an orifice plate 51 having a central polygonal axial hole 51^a for a similarly shaped portion 52 of the shaft 35. The plate 51 is mounted contiguously with the disc 45 and has a number of orifices 53, 54, 55, 56 and 57, graduated in size from the largest orifice 53 to the smallest orifice 57, which are arranged for selective alignment with the axial hole 47^a of the valve seat ring 45. The largest orifice 53 may be of any desired size, but at most no larger than the hole 47^a. I have shown said largest orifice somewhat smaller than the hole 47^a. A shutoff part 58 on the plate 51 is provided between the orifices 53 and 57. From the foregoing it can be seen that the orifice plate 51 will rotate bodily with the shaft 35 and that said shaft, by means of the pin and hole bearing 48 and 49, is journaled in the disc 45 which is seated in the ring 41. Because said ring 41 and the disc 45 are eccentric with respect to the plate 51 and the shaft 35, there is no tendency to cause said disc 45 to rotate when the

shaft 35 is rotated. Accordingly, the plate 51 rotates with relation to the disc 45 and by such rotation the orifices 53 to 57, inclusive, can be selectively positioned in alignment with the disc hole 47^a.

The manual means 16 is shown as comprising a handwheel 60 secured to the shaft 35. By means of said handwheel, the desired aligned selection of the hole 47^a with the holes 53 to 57 can be obtained. Said handwheel 60 also serves as means whereby an endwise pull can be exerted on the shaft 35 for the purpose of longitudinally separating the faces 44 and 46 of the ring 41 and the disc 45, respectively. I provide means for maintaining engagement of the faces 44 and 46 and for this purpose I provide a coil spring 61 around the shaft 35 and arranged between abutments afforded by the plate 51 and the plate 21. In order to prevent complete disassociation of the disc fins 47 and the passage 43, I provide a suitable shoulder 62 on the shaft 35 which cooperates with the plate 21 to limit the endwise movement of the shaft to at all times retain engagement of said disc fins 47 and said passage 43.

The visual means 17 may be variously made. I have shown an index pointer 63 carried by the shaft 35 between the gland 38 and the handwheel 60 and mounted to rotate with said shaft and a plurality of suitable radially arranged index marks 64 or the like, on the outer flat face of the plate 21 associated with the index pointer 63 for visual indication of the selected alignment between the hole 47^a and the orifices 53 to 57.

Since pressure varies during the life of a well and from well to well, the flow bean which I have provided will meet changing conditions with the greatest ease. The flow through the bean can be kept at its greatest efficiency by suitable and quick alignment of one of the orifices 53 to 57 with the hole 47^a so that varying fluid supply from the inlet flow passage 31 can be regulated to obtain a uniform or any desired flow in the outlet passage 32. Further, when the fluid enters the chamber 12 from the inlet passage 31 it seeks exit through the flow aligned orifice in the plate 51. A slightly turbulent and sluggish flow in the chamber 12 is created, reducing the abrasive effect of the sands and other particles upon the surfaces of the orifice plate 51 and the aligned orifice. Longer useful life of this part is, therefore, assured. The orifice plate functions as a positive restriction which has the additional property of being selective as to size. Long operation may cause the chamber 12 to fill up and become sand clogged. This condition can be quickly remedied by a pull on the handwheel 60 to open the passage 47^a directly to the chamber 12. The flow from the inlet passage 31 to the outlet passage 32 now being substantially unrestricted, the fluid will wash through the chamber 12 at an unhindered flow rate and clear the same of sand accumulations. Release of the handle 60 restores the flow bean to desired and normal operation. Shutoff of the flow bean is quickly obtained by aligning the orifice plate part 58 with the outlet passage and, since the disc 45 and the plate 51 and the seat ring 41 are arranged in pressure-closed relation, certain shutoff is obtained.

Having described only a typical preferred form and application of my invention, I do not wish to be limited or restricted to the specific details herein set forth, but wish to reserve to myself any variations or modifications that may appear

to those skilled in the art and fall within the scope of the following claims.

Having described my invention, I claim:

1. A flow controlling device of the character described including, a housing having inlet and outlet passages, a seat in the housing with an opening concentric with and passing flow to the outlet passage, a disc resting on the seat and having a flow opening concentric with the opening in the seat and communicating therewith, an orifice plate seated on the disc and rotatable about an axis laterally spaced from that of the outlet passage and having a plurality of flow controlling orifices to be positioned one at a time in register with the flow opening of the disc, operating means for rotating the plate from the exterior of the housing, and means coupling the disc and plate for removal from the housing as a unit.

2. A flow controlling device of the character described including, a housing having inlet and outlet passages, an annular seat in the housing concentric with the outlet and passing flow to the outlet passage, a disc resting on the seat and having a flow opening concentric with the seat, a rotatable orifice plate seated on the disc and having an axis eccentric thereto and having an arcuate series of flow controlling apertures concentric with the axis of the disc, the apertures being concentrically registerable, one at a time with the flow opening, and means operable to rotate the plate from the exterior of the housing.

3. A flow controlling device of the character described including, a housing having inlet and outlet passages, an annular seat in the housing concentric with the outlet passage, a disc concentric with and resting on the seat and having a flow opening therethrough, an orifice plate with a curved series of flow controlling apertures, and means pivotally connecting the plate and disc on an axis concentric with the series of apertures and eccentric to the axis of the disc for rotation of the plate to register the apertures with the opening one at a time.

4. A flow controlling device of the character described including, a housing having inlet and outlet passages, an annular seat in the housing concentric with the outlet passage, a disc concentric with and resting on the seat and having a flow opening therethrough, an orifice plate with a curved series of flow controlling apertures, and means pivotally connecting the plate and disc on an axis concentric with the series of apertures and eccentric to the axis of the disc for rotation of the plate to register the apertures with the opening one at a time including, a shaft projecting into the housing and having driving engagement with the plate and rotatably supporting the disc adjacent the plate.

5. A flow controlling device of the character described including, a housing having inlet and outlet passages, an annular seat in the housing concentric with the outlet passage, a disc concentric with and resting on the seat and having a flow opening therethrough, means guiding the disc concentric with the seat, an orifice plate with a curved series of flow controlling apertures, and means pivotally connecting the plate and disc on an axis concentric with the series of apertures and eccentric to the axis of the disc for rotation of the plate to register the apertures with the opening one at a time.

6. A flow controlling device of the character described including, a housing having inlet and outlet passages, a shaft supported by the housing eccentric to the outlet passage, a member seated

in the housing with an opening communicating with the outlet passage, and a plate mounted concentric on the inner end portion of the shaft to be rotated thereby on an axis eccentric to the opening, the inner end portion of the shaft being rotatably engaged with the said member with said member forming the sole support for the said portion of the shaft.

7. A flow controlling device of the character described including, a housing having inlet and outlet passages, a shaft supported by the housing eccentric to the outlet passage, a member seated in the housing with an opening communicating with the outlet passage, a plate mounted concentric on the inner end portion of the shaft to be rotated thereby on an axis eccentric to the opening, the inner end portion of the shaft being rotatably engaged with the said member with said member forming the sole support for the said portion of the shaft, and means retaining the said member on said portion of the shaft to be in coupled engagement with the plate.

8. A flow controlling device of the character described including, a housing having inlet and outlet passages, an annular seat ring threaded into the housing concentric with the outlet passage, a disc concentric with and resting on the seat and having a flow opening therethrough, an orifice plate with a curved series of flow controlling apertures, and means pivotally connecting the plate and disc on an axis concentric with the series of apertures and eccentric to the axis of the disc for rotation of the plate to register the apertures with the opening one at a time.

9. A flow controlling device of the character described including, a housing having inlet and outlet passages, an annular seat ring threaded into the housing concentric with the outlet passage, a disc concentric with and resting on the seat and having a flow opening therethrough, means guiding the disc concentric with the seat, an orifice plate with a curved series of flow controlling apertures, and means pivotally connecting the plate and disc on an axis concentric with the series of apertures and eccentric to the axis of the disc for rotation of the plate to register the apertures with the opening one at a time.

10. A flow controlling device of the character described including, a housing having inlet and outlet passages and an access opening provided with a removable closure, a member seated in the housing and normally stationary therein and having an opening communicating with the outlet passage, a multiple apertured plate in the housing seated on said member and shiftable relative thereto to control flow to the outlet passage, and a single means operating the plate within the housing and coupling the plate and said member as a unit for free relative rotation and for simultaneous removal from the housing through the access opening.

11. A flow controlling device of the character described including, a housing having inlet and outlet passages and an access opening provided with a removable closure, a seat ring threaded in the housing concentric with the outlet passage, a disc seated on the ring and having an opening communicating with the outlet passage, means guiding the disc centrally of the ring, a shaft entering the housing through the closure eccentric to the outlet passage and having its inner end rotatably engaged with the disc, means retaining the disc on the shaft, and a plate carried by the shaft to rotate therewith and located to seat on the disc and having a series of flow

controlling apertures concentric with the shaft and registrable with the opening in the disc one at a time.
